UNITED STATES PATENT OFFICE

UTAH F. FULTZ, OF DALLAS, TEXAS

DESIGN FOR A POSTER SIGN

Application filed April 8, 1929. Serial No. 30,807. Term of patent 7 years.

To all whom it may concern:

Be it known that I, UTAH F. FULTZ, a citizen of the United States, residing at Dallas, in the county of Dallas and State of Texas, have invented a new, original, and ornamental Design for Poster Signs, of which the following is a specification, reference being had to the accompanying drawing, forming part thereof.

I claim:

The ornamental design for a poster sign, as shown.

UTAH F. FULTZ.
